ELDRIDGE I. LA COUNT, OF WORCESTER, MASSACHUSETTS, ASSIGNOR TO ORCUTT AUTOMATIC TRAIN CONTROL COMPANY, OF WORCESTER, MASSACHUSETTS, A CORPORATION OF ARIZONA.

APPARATUS FOR ELECTRICALLY CONTROLLING AIR-BRAKES.

1,336,465.

Specification of Letters Patent. Patented Apr. 13, 1920.

Application filed April 2, 1919. Serial No. 286,903.

To all whom it may concern:

Be it known that I, ELDRIDGE I. LA COUNT, a citizen of the United States, and a resident of Worcester, in the county of Worcester 5 and State of Massachusetts, have invented a new and useful Improvement in Apparatus for Electrically Controlling Air-Brakes, of which the following is a specification.

My invention relates to apparatus of the 10 general type shown in my Patent 1,285,246 dated November 19, 1918, for electrically controlling air brakes and is particularly adapted for use in train controlling systems having the general characteristics of that 15 shown in the patent to Orcutt, 1,285,345 dated November 19, 1918.

In such train controlling systems provided with my electrical air brake control, 20 circuits carried by the train are looped into road-bed circuits formed in part by the block ahead of that in which the train is running and if such block has been rendered unsafe as by an open switch or the presence of another train therein or if the road-bed 25 apparatus is disorganized and incapable of performing its intended function, a train carried magnet will be deenergized and the brakes applied. In order to release the 30 brakes the engineer throws the handle of a rotary valve from running position to cut 35 out position, and this may be done as soon as the train brakes have been applied irrespective of the condition of the block ahead or the reduction of the speed of the train.

One of the objects of my invention is to 40 provide means whereby the handle of the rotary valve will be locked in running position until the train has been brought to a full stop or else the speed thereof reduced to 45 a predetermined rate. Another object is to provide means whereby a train which has automatically been stopped cannot be driven at more than a predetermined speed until it passes out of the block the condition of 50 which caused the train to be stopped and then only in the event that the next block ahead is safe.

The drawing which accompanies and 55 forms a part of this specification represents in diagram the preferred embodiment of my invention; but it will be understood that both the apparatus and the circuit arrangements therein shown may be materially modified by those skilled in the art without

departing from the invention as defined by 55 the appended claims.

Each block section A, B and C consists of the continuous rail 1 and one of the sectional rails 2, 2', 2'', the component parts of each section of the sectional rail being electrically connected and each section being insulated from its contiguous sections. Located 60 near the end of each section is a ramp 3 connected through the resistance 4 to the sectional rail of the block ahead and the latter 65 by means of conductor 5 is connected to one terminal of the track magnet 6 which preferably is of the hollow core solenoid type shown in my prior patent above referred to and has an armature 7 movable between the 70 lower end of the inclosing sheath 8 and the back stop 9. The other terminal of said track magnet is connected by the wire 10 to the continuous rail. The shorter ramp 11, arranged opposite the ramp 3 is connected 75 by the conductor 12 to the brush 13 and the coöperating brush 14 is connected through the resistance 15 to the return wire 10. The brushes normally rest on one of the insulating portions of the track switch 16 which is 80 provided with a conducting ring 17.

The positive terminal of the generator 18 carried by the train is connected to one terminal of the train-stopping magnet 19 preferably similar in construction to the track 85 magnet and having an armature 20 movable between the lower end of the inclosing sheath 21 and the back stop 22. The upper end of the plunger of the solenoid 19 carries the valve 23 which normally closes communication between the passageway 24 and the port 25. The lower end of the plunger is provided with a commutator having insulating portions 26 and the conducting ring 27 arranged between the same. The brush 28 which is always in contact with the conducting portion of the commutator is connected to the negative pole of the generator. The brush 29 which is in contact with the conducting ring 27 when the valve 23 is on 100 its seat and which breaks contact with said ring when the solenoid is deenergized, is connected to the positive brush of the generator through the safety signal lamp 30. The brush 31 which is in contact with one 105 of the insulating parts of the commutator when the solenoid is energized and which is arranged to make contact with the ring 27

when said solenoid is deenergized is connected to the positive brush of the generator through the danger signal lamp 32.

The circuit of the solenoid 19 is completed by the conductor 33, the brushes 34, 35, which under certain conditions are in contact with the conducting ring 36 of the centrifugally-actuated switch 37, the conductor 38, which is connected to said brush 35, the shoe 39, one end of which is fixed to the engine, the other resting on the conducting portion of the stop 40, the resistance 41 and the return wire 42 which is connected to the negative brush of the generator.

The operation of the system as so far described, assuming that there is an electrical connection between the brushes 34 and 35 is as follows: When the shoe 43, fixed to the engine and electrically connected to the positive pole of the generator, makes contact with the ramp 3 there will be a closed circuit through the solenoid 6 by way of said shoe and ramp, sectional rail 2, conductors 5 and 10, rail 1, rolling contact 44 which may be a wheel of the locomotive and thence by return wire 42 to the generator.

The resulting energization of the track magnet 6 will throw the track switch 16 to such position, upwardly in the particular instance shown in the diagram, that the brushes 13, 14 will be in contact with the ring 17. Normally the circuit of the train-stopping magnet 19 is closed through the resistance 41 as above set forth, but as soon as the shoe 39 rides up on the ramp 11 the circuit of said magnet will be momentarily opened at the stop 40 and then instantly closed by way of the conductor 12, brushes 13 and 14, ring 17, resistance 15 which is substantially equivalent to the resistance 41, conductor 10, rail 1 and return wire 42.

However, if the block B has been rendered unsafe for any of the reasons above given, the solenoid 6 will not be energized when the shoe 43 strikes the ramp 3 and the track switch will remain in the position indicated, so that when the shoe 39 strikes the ramp 11 the solenoid 19 will become deenergized, the valve 23 will leave its seat and the brakes will be set in the manner described in my patent aforesaid. At the same time there will be a circuit through the danger signal lamp 32 by way of the brush 31, ring 27, and brush 28, the circuit of the safety signal lamp 30 being broken between the brush 29 and the ring 27.

As soon as the shoe 39 has passed over the ramp 11 the circuit of the solenoid 19 will be closed and the valve 23 reseated. The engineer may now release the brakes by throwing the handle 45 to cut-out position thereby actuating the rotary valve located in the casing 46 which functions in the manner set forth in my Letters Patent above mentioned.

It is obviously desirable that the engineer should be prevented from releasing the brakes until the train is brought to a complete stop or else its speed reduced to a safe rate. To effect this result I provide a magnetically actuated lock so arranged that the circuit thereof will be closed unless the train is at a standstill or else traveling at a predetermined and safe rate. In the particular embodiment of my invention shown in the drawings the plunger 47 of the solenoid 48 having the armature 49 which rests against the back stop 50 upon the deenergization of the solenoid 48, is arranged to pass through registering apertures bored in extensions of the handle 45 and the casing 46 and thus lock the rotary valve in running position as long as the circuit of the solenoid 48 is closed. The closure of said circuit is determined by the switch 37 arranged to be actuated by the governor 51 which is attached to a shaft provided with the bevel gear 52, the latter meshing with a gear (not shown) secured to a rotating member of the engine. The brushes 53, 54 to which the terminals of the circuit of the magnet 48 respectively are connected, are arranged to make contact with one of the insulating portions of the switch 37 and thereby open the circuit of said magnet only when the train is at rest or only when it is traveling at a very low rate of speed, for example, six miles an hour. Just as soon as the train is put in motion, or as soon as it exceeds a predetermined safe rate of speed, the governor 51 will raise the switch 37 so that the conducting ring 55 will be brought into electrical contact with the brushes 53, 54 and thereby close the circuit of the magnet 48 which will lock the handle 45 in running position.

After a train has been brought to a stop it is desirable that its speed be automatically controlled until it passes out of the unsafe block and for this purpose I have arranged the circuit of the train-stopping magnet 19 to be controlled by the governor 51. In the present instance the brushes 34, 35 which are included in the circuit of the magnet 19 make electrical contact with the conducting ring 36 only so long as the speed of the train is below a predetermined rate, as for example, six miles per hour. The rate of speed to which the train will be limited while passing through a dangerous block will be determined by the position of the ring 36 with respect to the insulating member of the switch 37, assuming the brushes to be fixed, or on the position of the brushes with respect to the ring, assuming the latter to be fixed, when the governor is at rest. In the present instance I have assumed that the brushes will be fixed and that the ring 26 may be adjusted longitudinally of the insulating cylinder 37.

and held in adjusted position by the set screw 56.

When the speed of the engine is higher than the predetermined safe rate above mentioned, the governor will move the switch to such position that the ring 36 passes beyond the fixed brushes 34, 35 and brings the latter in contact with the insulating member to which said ring is fixed, and when this occurs, the circuit of the magnet 19 will still remain closed, unless the block through which the train is traveling is dangerous, by way of the shunt 57, the terminals of which are connected to the brushes 34, 35 respectively and to the brushes 58, 59 which remain in electrical contact with the conducting ring 60 of the switch 61 under normal conditions.

However, if the block ahead of that in which the train is running has been rendered unsafe and the circuit of the solenoid 19 broken in the manner above set forth so that as aforesaid the brush 31 will be in contact with the ring 27, there will be a circuit through the solenoid 62 as follows: From the positive pole of the generator to the point *a*, thence around the shunt wires 63, 64 to the solenoid 62, and then back to the generator by the brush 31 and conducting ring 27.

The resulting energization of the solenoid 62 will throw the switch 61 to the left so that one of the insulating portions thereof will come in contact with the brushes 58, 59, thereby opening the shunt circuit 57, and such circuit will remain open until the train passes out of the dangerous block, as hereinafter set forth, such blocks being assumed, of course, to have been placed in a safe condition before the train passes out of it and the block ahead being assumed to be safe.

It will be apparent therefore that as long as the shunt 57 is open the speed of the train cannot exceed a predetermined rate without opening the circuit of the solenoid 19 between the brushes 34, 35 and the insulating member of the switch 37.

As soon as the shoe 65 which is fixed to the train strikes the ramp 11 at or near the end of the block, the unsafe condition of which was indicated before the train entered therein, there will be a circuit through the solenoid 66 as follows: From the positive pole of the generator to the point *a*, conductors 63, 64, solenoid 66, shoe 65, ramp 11, conductor 12 to brush 13 of the track switch and thence back to the generator by wire 10, rail 1 and wire 42. Inasmuch as the shoe 43 has made contact with the ramp 3 before the shoe 65 has struck the ramp 11, it follows that the solenoid 6 will be energized if the block ahead is safe and that by the time shoe 65 has made contact with ramp 11, the brushes 13 and 14 will be on

the ring 17. The circuit of the solenoid 66 will therefore be completed through said brushes, wire 10, continuous rail 1, rolling contact 44 and return wire 42. The energization of said solenoid 66 will restore the switch 61 to its normal position as shown in the diagram, said switch being attached to the end of the rod 67 provided with the oppositely arranged armatures 68, 69 which are arranged to be attracted by the solenoids 62 and 66, respectively.

It will be understood of course that the governor 51 is shown in its position of rest.

Preferably the lower end of the ring 36 is beveled so that the coöperating brushes which usually are spring-pressed will not prevent said ring from sliding under them as the switch 37 moves downwardly.

Having thus particularly described an illustrative embodiment of my invention without, however, limiting the same thereto, what I claim as new and desire to secure by Letters Patent is:

1. Apparatus for electrically controlling air brakes comprising in combination brake releasing means, electro-magnetic means for locking the same in running position and a centrifugally-actuated switch comprising an insulating portion and a conducting portion, the circuit of said electro-magnetic means being opened through said insulating portion only when the train is stationary or is traveling at a speed less than a predetermined rate.

2. Apparatus for electrically controlling air brakes comprising in combination a rotary valve, electro-magnetic means for locking the same in running position and a centrifugally-actuated switch comprising an insulating portion and a conducting portion, the circuit of said electro-magnetic means being opened through said insulating portion only when the train is stationary or is traveling at a speed less than a predetermined rate.

3. Apparatus for electrically controlling air brakes comprising in combination a rotary-valve casing, a valve handle mounted thereon, a vertically disposed solenoid located below the top of said casing, a plunger for said solenoid constructed and arranged to lock said handle in running position and a centrifugally-actuated switch comprising an insulating portion and a conducting portion, the circuit of said solenoid being opened through said insulating portion only when the train is stationary or is traveling at a speed less than a predetermined rate.

4. Apparatus for electrically controlling air brakes comprising in combination a magnet carried by the train, an armature for said magnet, a valve actuated by said armature for setting the brakes, a circuit for the same, a centrifugally-operated switch hav-

ing a conducting portion and an insulating portion for opening and closing said circuit and means for adjusting the position of said conducting portion with respect to said insulating portion.

5. Apparatus for electrically controlling air brakes comprising in combination a train-stopping magnet carried by the train, a circuit for the same, a centrifugally-operated switch having a conducting portion and an insulating portion, the circuit of said magnet being closed through said conducting portion only when the train is stationary or is traveling at a speed less than a predetermined rate, and a shunt circuit connected around said switch for closing the circuit of said magnet when the speed of the train is equal to or exceeds said predetermined rate.

0 6. Apparatus for electrically controlling air brakes comprising in combination a train-stopping magnet carried by the train, a normally closed circuit for the same, a centrifugally-operated switch having a conducting portion and an insulating portion, said conducting portion being included in said circuit when the train is stationary or is traveling at a speed less than a predetermined rate, a shunt circuit connected around said switch for closing the circuit of said magnet when the speed of the train is equal to or exceeds said predetermined rate, electro-magnetically actuated means for opening said shunt circuit and means controlled by said train-stopping magnet for controlling said electro-magnetically actuated means.

35 7. Apparatus for electrically controlling air brakes comprising in combination a

train-stopping magnet carried by the train, 40 a normally closed circuit for the same, a centrifugally-operated switch having a conducting portion and an insulating portion, said conducting portion being included in said circuit when the train is stationary or 45 is traveling at a speed less than a predetermined rate, a shunt circuit connected around said switch for closing the circuit of said magnet when the speed of the train is equal to or exceeds said predetermined rate, 50 a track switch, and means controlled by said track switch for closing said shunt circuit.

8. Apparatus for electrically controlling air brakes comprising in combination a train-stopping magnet carried by the train, 55 a normally closed circuit for the same, a centrifugally-operated switch having a conducting portion and an insulating portion, said conducting portion being included in said circuit when the train is stationary or 60 is traveling at a speed less than a predetermined rate, a shunt circuit connected around said switch for closing the circuit of said magnet when the speed of the train is equal to or exceeds said predetermined rate, 65 a train-carried switch for opening and closing said shunt circuit, a solenoid for setting said train-carried switch to shunt-closing position, a track switch, a train-carried shoe electrically connected to said solenoid, a 70 ramp arranged to coöperate with said shoe and means electrically connecting said ramp to said track switch.

In testimony whereof, I have hereunto subscribed my name this 29th day of March, 75 1919.

ELDRIDGE I. LA COUNT.
